UNITED STATES PATENT OFFICE.

JOSEPH H. DEMERY, OF PHILADELPHIA, PENNSYLVANIA, ASSIGNOR TO MAX ZEITLER
ENGRAVING & SUPPLY CO., OF PHILADELPHIA, PENNSYLVANIA.

ATTACHMENT FOR POWER EMBOSSED PRESSES.

1,032,469.

Specification of Letters Patent. Patented July 16, 1912.

Application filed August 26, 1909. Serial No. 514,687.

To all whom it may concern:

Be it known that I, JOSEPH H. DEMERY, a citizen of the United States, residing at Philadelphia, in the county of Philadelphia and State of Pennsylvania, have invented 5 certain new and useful Improvements in Attachments for Power Embossing Presses, of which the following is a specification.

My invention relates to an improvement 10 in attachments for power embossing presses, and its object is to provide means for removing the surplus ink from the die or plate before the impression is made.

The invention consists in certain novel 15 features of construction and combinations of parts which will be hereinafter described and pointed out in the claims.

In the accompanying drawings, Figure 1 is a top plan view of my invention, Fig. 2 20 is a view in side elevation, Fig. 3 is a longitudinal vertical sectional view, Fig. 4 is a view in side elevation of the mechanism for actuating the rolls of cloth, Fig. 5 is a sectional view through the operating mechanism disclosed in Fig. 4, Fig. 6 is a view in 25 elevation of the bracket and roll for immersing the fabric, and Fig. 7 is a view in side elevation of the means for adjusting the upper wringing roll.

The upright 1, bracket 2, table 3 and inking mechanism 4 are old and form a part of the embossing presses now upon the market. The wiper-head 5 which is connected to a pivoted arm 6 is also old in the art and the 30 head is provided with a flexible pad 7 preferably of sponge-rubber. The shaft 8 is mounted on the bracket 2 and supports the roll of cloth or other material 9 which is conducted down into the tank 10 which is supported upon the bracket 2, the tank being provided with a liquid for saturating the cloth. Brackets 11 are connected to the tank and journaled in the brackets is a wringing roll 12. An upper wringing roll 40 35 45 13 is adjustably mounted in slots 14 formed in the brackets. Thumb-screws 15 are connected to the upper ends of the brackets and

bearing against the thumb-screws and rolls are coiled springs 16. By the adjustment of the thumb-screws 15 the moisture can be wrung from the fabric as it passes between the wringing rolls. However, it is the object of my invention to regulate this adjustment so that only a certain amount of the liquid will be removed from the cloth. 55

An immersing bracket 17 is supported in the tank 10, one end of the bracket being provided with a pin 18 which is adapted to enter a socket 19, the other end of the bracket being supported by a pin 20. The bracket 17 carries a roll 18^a beneath which the cloth 9 passes whereby the cloth is thoroughly saturated in the liquid before passing between the wringing rolls 12 and 13. The cloth passes from the upper wringing roll 13 down and beneath the wiper-head 5, then up and over an idler 21 and thence to a rotating or winding roll shaft 22. Loosely mounted upon the winding roll shaft 22 is a sprocket-wheel 23 and mounted upon the hub 60 65 70 75 80 85 90 95 of the sprocket-wheel is a gear-wheel 24, the gear-wheel being keyed to the sprocket-wheel by a key 25. A friction pad 26 is keyed to the shaft 22 and bears against the sprocket-wheel 23. A washer 27 keyed to the shaft 22 bears against the friction pad 26, and nuts 28, 28 regulate the frictional engagement between the sprocket-wheel 23 and the pad 26. A jack-shaft 29 is mounted upon the frame or upright 1 and is provided with two levels 30 and 31. Mounted upon the level 30 of the shaft is a gear-wheel 32 which is adapted to mesh with the gear-wheel 24. Connected to the gear-wheel 32 is a ratchet-wheel 33. A semi-circular cam 34 is mounted on the level 31 of the shaft 29 and bears against the shoulder 35 formed on the shaft, the cam 34 being provided with a handle 36 for shifting it to its different positions. Loosely mounted upon the cam is an arm 37 which is provided with a pawl 38 adapted to engage the ratchet-teeth of the ratchet-wheel 33. A lever 39 is connected to the arm 37 for causing the lever to be moved, whereby the pawl

38 will engage the ratchet-wheel 33 causing the gear-wheel 32 to be rotated, thereby transmitting rotary motion to the gear-wheel 24 and causing the cloth to be wound 5 upon the winding roll 22. The lever 39 is operated in any suitable manner and is intended to intermittently operate the ratchet-wheel, causing the cloth to be wound upon the winding roll.

10 A sprocket-wheel 40 is mounted on the lower wringing roll shaft 12. A sprocket chain 41 connects the sprocket-wheels 40 and 23 for causing the wringing roll 12 to be operated upon the operation of the winding roll 22. Suppose the die or plate has been inked by the inking mechanism and it is desired to remove the surplus ink from the die or plate: The winding mechanism is stationary and the wiper-head is caused to 15 be lowered to cause the moistened or dampened cloth to come in contact with the die or plate for removing the surplus ink. When the wiper-head 5 is raised the lever 39 will be operated, causing the pawl 38 to 20 engage the ratchet-teeth of the ratchet-wheel 33, thereby causing the ratchet-wheel to rotate and at the same time rotate the gear-wheel 32. The gear-wheel 32 transmits rotary motion to the gear-wheel 24 and the 25 sprocket-wheel 23. The winding shaft 22 will be caused to revolve and the wringing roll 12 will rotate through the sprocket-wheels 23 and 40 by their connection by the sprocket-chain 41, thereby causing the cloth 30 to be unwound from the shaft 8, drawing it through the tank 10 and between the wringing rolls 13 and 13 where a certain amount of moisture will be removed from the cloth, and as the winding roll 22 operates 35 the cloth will be wound thereon, bringing a new surface of the moistened cloth beneath the wiper-head 5 for the next operation.

A dog 42 is connected to the frame 1 and is adapted to engage the ratchet-teeth of 45 the ratchet-wheel 33 for holding the wheel against movement. The cam 34 is received beneath the pawl 38 and regulates the engagement of the pawl with the teeth of the ratchet-wheel. By moving the cam by the 50 handle 36 the pawl will engage the ratchet-wheel for causing the wheel to be revolved a greater or less distance, according to the direction in which the cam is moved. When the winding roll 22 has a tendency to move 55 farther than the supply of cloth or other material will warrant, the friction between the friction pad 26 and the sprocket-wheel 23 is sufficient to cause the winding roll shaft to remain stationary and to allow the 60 sprocket-wheel 23 to move sufficiently to cause the wringing roll 12 to operate to cause a sufficient supply of cloth to be unwound from the shaft 8 to permit of the movement of the wiper-head 5 without

straining or stretching the cloth in the removal of the surplus ink from the die or plate.

Heretofore, the die or plate has been operated upon by paper or cloth for removing the surplus ink, but there are many objections to the use of the cloth or paper, as it requires a great deal of power to create a sufficient impression to absorb or remove the ink from the plate or die. With my improvement I moisten the fabric or cloth and cause it to pass through wringing rolls and by the adjustment of the upper wringing roll 13 sufficient pressure will be formed for removing enough of the water or liquid from the cloth to obtain the proper removal 70 of the surplus ink from the die or plate. By moistening or having the cloth sufficiently moist the surplus ink can be removed from the die or plate without smearing; it will clearly cut the ink from the die and gives 75 a richer tone to the work. It will not squash or make a feather edge to the printing, which is noticeable with the dry paper or cloth. The dry paper or cloth has a tendency to remove or absorb all of the moisture 80 from the die or plate due to the fact that a great deal of pressure is necessary to cause the removal of the ink from the die or plate by the dry paper or fabric.

Having fully described my invention, 95 what I claim and desire to secure by Letters-Patent, is:

1. A power embossing press comprising a plate, inking mechanism for applying ink to the plate, a pad, a tank adapted to have 100 a liquid therein, wringing rolls, a cloth fed through the tank and between the wringing rolls and across the surface of the pad, a winding roll for one end of the cloth, means for imparting an intermittent motion to the 105 winding roll, and means transmitting said intermittent motion from the winding roll to one of the wringing rolls, whereby positive movement is imparted to the latter in unison with that of the winding roll.

2. A power embossing press comprising a plate, inking mechanism for applying ink to the plate, a pad, a tank adapted to have a liquid therein, wringing rolls, a cloth fed through the tank and between the wringing 115 rolls and across the surface of the pad, a winding roll for one end of the cloth, means for imparting an intermittent motion to the winding roll, and means transmitting said intermittent motion from the winding roll 120 to one of the wringing rolls, and means for adjusting one at least of the wringing rolls, whereby to regulate the wringing pressure upon the cloth.

3. A power embossing-press comprising 125 inking mechanism for applying ink to a plate, a tank having a liquid therein, a cloth passing through the tank, upper and lower

wringing rolls between which the cloth passes for removing the moisture therefrom, a sprocket-wheel of the lower wringing roll, a winding shaft having a gear-wheel and sprocket-wheel mounted thereon, a chain connecting the sprocket-wheel with the sprocket-wheel of the lower wringing roll, a jack-shaft having a gear-wheel and ratchet-wheel mounted thereon, and means

for operating the ratchet-wheel whereby motion is transmitted to the winding shaft on the wringing roll.

In testimony whereof I affix my signature, in the presence of two witnesses.

JOSEPH H. DEMERY.
